UNITED STATES PATENT OFFICE.

CYRUS TAYLOR, OF DENVER, COLORADO.

RAILWAY-RAIL JOINT.

SPECIFICATION forming part of Letters Patent No. 325,458, dated September 1, 1885.

Application filed December 2, 1884. (No model.)

To all whom it may concern:

Be it known that I, CYRUS TAYLOR, a citizen of the United States, residing at Denver, in the county of Arapahoe and State of Colorado, have invented certain new and useful Improvements in Railway-Rail Joints, of which the following is a full, clear, and exact description, reference being had to the accompanying drawings, forming part of this specification, in which—

Figure 1 is a perspective view showing the meeting ends of the rails, and with my improvements attached. Fig. 2 is an elevation from the opposite side; and Fig. 3 is a sectional view on the line $x-x$ of Fig. 2.

Similar letters of reference indicate corresponding parts in the several figures.

My invention relates to an improved method for splicing railway-rail joints; and it consists in the several combinations of devices hereinafter claimed and explained.

To enable others skilled in the art to make and use my invention, I will now proceed to describe the exact manner in which I have carried it out.

In the said drawings, A and A' represent the ordinary railway-rails, and B represents the space between the ends of the rails.

To protect the ends of the rails from the repeated blows given to them by the wheels of a moving train, and to prevent the shock or jolt that is communicated to the rolling-stock of the road when the ordinary splice is used, I place upon the outside of the rails at the joint B what I term an "outside bridge-bar," C. This bar is of a construction similar to that shown in Fig. 1, and so arranged that its lower surface snugly fits and rests upon the base or flange a of the rails, while its upper part, after closely fitting the space between the head of the rail and the flange a extends upwardly to and flush with the top or tread of said rail, thereby forming a part of the track upon which the wheels of the locomotive and cars roll. This bridge-bar is provided with bolt-holes b , corresponding with similar holes formed in the rails, as shown at c , Fig. 3, while another bolt-hole, d , is formed at or about the center of said bridge-bar, and with suitable bolts assist in keeping the parts in position, and forming, substantially, a smooth and rigid joint, thereby avoiding the

annoyance and danger incident to a rough or uneven joint.

Upon the side of the rail and opposite to the bridge-bar C is placed a splice-bar, D. This is the ordinary splice-bar, corresponding to the configuration of the rail between the flange a and the head, and is provided with square tapering holes e and f , arranged in alignment with the holes b , c , and d , the object of these tapering bolt-holes e being to enable me to bring the heads of the bolts E flush with the outer face of the inside splice-bar, thereby protecting them from the flanges of the moving wheels.

Upon reference to Fig. 1 it will be seen that the bridge-bar C is so constructed that its upper surface has a gradual slope from near the center toward each end, as shown at g , the lowest points of the incline falling slightly below the surface or tread of the rail. The object of this construction is to allow the wheels to gradually rise upon the bridge-bar and avoid any abrupt obstruction.

It will also be seen that I pass my central bolt through the intervening space between the ends of the rails, thus giving a more perfect support to the extreme ends of the rails, where the support is most required.

I am thus enabled by the foregoing-described device to furnish a substantial joint for the ends of the rails, and one in which any length of rails may be used that would be practical in the construction of a road.

Having thus described my invention, what I claim as new, and desire to secure by Letters Patent, is—

The combination, with the rails A and A', of the bridge-bar C, the upper surface of which inclines downwardly from its center toward each end, and having an enlarged central portion U-shaped in longitudinal section, a bolt passing through this enlarged portion and between the ends of the rails, a splice-bar provided with square tapering holes, and suitable bolts with square heads passing through the bars and uniting the parts, as herein described.

CYRUS TAYLOR.
